A. PEARSALL.
MACHINE FOR WELDING BELLows PIPES.

No. 21,359.

Patented Aug. 31, 1858.

UNITED STATES PATENT OFFICE.

A. PEARSALL, OF NASHVILLE, TENNESSEE.

WELDING BELLows-PIPE.

Specification of Letters Patent No. 21,359, dated August 31, 1858.

To all whom it may concern:

Be it known that I, A. PEARSALL, of Nashville, in the county of Davidson and State of Tennessee, have invented a new and Improved Machine for Welding Bellows Pipes or Nozzles; and I do hereby declare that the following is a full, clear, and exact description of the same, reference being had to the annexed drawings, making a part of this 10 specification, in which—

Figure 1, is a side view of my invention. Fig. 2, is a front sectional view of ditto taken in the line α , α , of Fig. 1. Fig. 3, is a perspective view of a nozzle before being 15 welded.

Similar letters of reference indicate corresponding parts in the several figures.

This invention consists in the employment or use of an inclined mandrel, clamps, and 20 welding roller arranged as hereinafter fully shown and described, whereby the seams or joints of bellows pipes or nozzles may be closed and welded in a very expeditious and perfect manner.

25 To enable those skilled in the art to fully understand and construct my invention I will proceed to describe it.

A, represents the base of the machine which may be of cast metal and B, is an upper post attached thereto at one end.

30 C, is a mandrel of taper or conical form and attached to the post B, so as to project over the base A, in an inclined position as shown clearly in Fig. 1, the form and dimensions of the mandrel corresponding to the form and dimensions of the pipes or nozzles to be welded.

35 D, D, are two uprights attached to the base A. Between the upper ends of the uprights D, D, the shanks a , a , of two clamps E, E, are placed, said shanks being fitted loosely on a rod b , and crossing each other so that as the lower ends of the shanks are drawn toward each other the clamps E, E, 45 will have a corresponding movement.

The clamps E, E, may be described as being longitudinal halves of a hollow cone or a form approximating thereto so as to conform to the shape of the mandrel C, see 50 Fig. 2, a clamp being at each side of the mandrel.

The lower ends of the shanks a , a , are attached by a wire or chain c , to a treadle G, connected by a fulcrum pin d , to the post B.

55 This treadle passes through slots in the uprights D, D. The lower end of each shank

a , a , has a spring e , bearing against it, said springs having a tendency to keep the lower ends of the shanks thrown outward from each other.

60

To the upper end of post B, two inclined bars H, H, are attached. These bars are slotted longitudinally and horizontally to receive the axis or shaft f , of a roller I, the periphery of which is made slightly concave corresponding to the periphery of the mandrel C. The slotted bars H, H, serve as guides for the roller I.

65

J, J, are two spring catches which are attached to the post B, and which retain the roller I, at the upper parts of the bars H, by catching over the axis f , see Fig. 1, a spring catch J, being at each end of the axis f . The spring catches J, are connected by a wire or chain g , with the treadle G.

70

The operation is as follows: The pipes or nozzles K, are formed of sheet metal and bent in proper form, one edge overlapping the other as shown clearly in Fig. 3. The pipes or nozzles are properly heated at the edges and placed one at a time on the mandrel C. The foot of the operator is then placed on the end of treadle G, and said treadle depressed.

75

By this operation the clamps E, E, are pressed against the pipe or nozzle which is thereby retained on the mandrel and the spring catches J, J, are, by the same movement of the treadle, depressed and the roller I, allowed to descend down and over the edges of the pipe or nozzle closing the seam or joint and by its own gravity perfectly welding the same, the upper edges of the clamps being sufficiently far apart to expose fully the seam or joint. The roller I, is then moved back and 80 retained by the spring catches J, J, the clamps E, E, being distended by the springs e , e , which in connection with the spring catches J, J, elevate the treadle G. Another pipe or nozzle is then heated and placed on the mandrel C, and the operation repeated.

85

90 Having thus described my invention what I claim as new and desire to secure by Letters Patent, is,

95

The inclined mandrel C, clamps E, E, and roller I, combined and arranged for joint operation substantially as and for the purpose herein set forth.

100

A. PEARSALL.
